UNITED STATES PATENT OFFICE.

ALBERT JOHNSON, OF CHICAGO, ILLINOIS.

DETACHABLE BUTTON.

SPECIFICATION forming part of Letters Patent No. 674,006, dated May 14, 1901.

Application filed October 22, 1900. Serial No. 33,893. (No model.)

To all whom it may concern:

Be it known that I, ALBERT JOHNSON, a citizen of the United States, residing at Chicago, in the county of Cook and State of Illinois, have invented certain new and useful Improvements in Detachable Buttons, of which the following is a specification.

The object of this invention is the production of a strong simple button having means for readily attaching it to the cloth of a garment and detaching it therefrom, which means is capable of being securely locked when the button is in position and is easily released when it is desirable to remove the button from the garment.

In the accompanying drawings, Figure 1 is a central section through the button, showing the same secured to the waistband of a garment, the latter being represented in section. Fig. 2 is a rear side view of the button, showing the same in a locked position. Fig. 3 is a similar view of the button, showing it unlocked. Fig. 4 is a side elevation of the button, its parts being in the position as represented by Fig. 3 looking in the direction of the arrow 4 in said figure. Fig. 5 is section on dotted line 5 5 of Fig. 3, showing the fastening-pin open upon its hinge-support. Fig. 6 is a section on dotted line 6 6 of Fig. 2, showing the fastening-pin closed and locked. Fig. 7 is a section on dotted line 7 7 of Fig. 6, showing the keeper for the free ends of the fastening-pin, said pin being removed from the keeper.

Like letters of reference indicate corresponding parts throughout the several views. In the production of a button embodying this invention I provide a body portion A of a generally circular outline, ordinarily formed by stamping it with suitable dies from sheet metal. One side of the body portion forms the face A' of the button. The body portion A is provided with a rearwardly-extending overturned portion A², which constitutes the keeper for the free ends of the fastening-pin, to be later described. One end of said keeper is closed at A⁴, as said pin is intended to enter from one side and be withdrawn from the same side of the keeper, and in its upper side said keeper is provided with a depression A³ for receiving one of the points of said pin and locking said button in a closed position.

A member B, circular in its general outline, is pivotally secured by means of the rivet B' to the body portion A of the button, said pivotal bearing being at or near the center of said body portion A. The pivotal member B, like the body portion A, is stamped from a sheet of metal and is provided with the integral strap B², formed with the loop B³ near the periphery of said pivotal member B and extending across the center of said member. This strap B² has a suitable opening for receiving the pivotal rivet B', and recesses B⁴ and B⁵ are formed in the edge of said pivotal member B opposite the side to which said loop B³ is attached, which recesses are intended to receive the points of the attaching-pin, to be next described. A curved two-part fastening-pin C is hinged to said member B, the middle portion C' of said curved pin passing through the loop B³. The pin C has two pointed ends C² and C³ and is formed so that the point C³ normally stands slightly above the point C² and so that when the latter point is in contact with the body portion A the point C³ is raised slightly from said body portion. It will thus be seen that when said pin is within the keeper A² the point C³ will engage the depression A³ and hold said member B and the fastening-pin C from accidental rotation with reference to the body portion A.

In practice the button is secured to the garment by inserting the points C² and C³ of the pin C through the cloth and back again, closing said pin upon its hinge-bearing, so that its points C² and C³ lie in contact with the rear side of the body portion A, and by rotating said body portion on the pivot B' until the points C² and C³ lie within the keeper A² and the point C³ in engagement with the depression A³ in said keeper. To detach the button, the point C³ is depressed from engagement with the depression A³ and the body portion of the button rotated to remove said points from said keeper. When withdrawn from the keeper, the pin C is free to open upon its hinge connection and be withdrawn from the fabric.

I claim as my invention—

1. In a detachable button, in combination, a body portion; a member having a pivotal connection with said body portion; a fastening-pin hinged on said pivotal member; and

means on said body portion for securing the free end of said fastening-pin.

2. In a detachable button, in combination, a body portion having a keeper; a member having a pivotal connection with said body portion; and a fastening-pin hinged on said pivoted member, the free end of said fastening-pin being adapted to engage said keeper.

3. In a detachable button, in combination, 10 a body portion having a keeper, said keeper having a depression; a member having a pivotal connection with said body portion; and a two-part fastening-pin hinged on said pivoted member, the free end of said fastening- 15 pin being adapted to engage said keeper, and one of the points of said two-part pin to enter the depression in the keeper, to lock said pin in engagement therewith.

4. In a detachable button, in combination, 20 a body portion having a keeper; a member having a pivotal connection with said body portion; a strap formed integral with said pivotal member; a loop formed by said strap; and a fastening-pin hinged in said loop, the 25 free end of said fastening-pin being adapted to engage said keeper.

5. In a detachable button, in combination, a body portion having a keeper; a member having a pivotal connection with said body 30 portion; a strap formed integral with said pivotal member; a loop formed by said strap; and

a two-part fastening-pin extending through said loop, and being thereby hinged to said pivotal member, the free end of said fastening-pin being adapted to engage said keeper. 35

6. In a detachable button, in combination, a body portion having a keeper with a depression therein; a member having a pivotal connection with said body portion; a strap formed integral with said pivotal member; a loop in 40 said strap; and a two-part fastening-pin extending through said loop, and thereby having a hinge connection with said pivotal member, one point of said pin being raised to engage said depression, and to lock said pin with 45 relation to said body portion.

7. In a detachable button, in combination, a body portion having a keeper formed integral therewith; a member having a pivotal connection with said body portion; a strap 50 formed integral with said pivotal member, and bent to form a loop; a rivet for securing said strap to the face of said pivotal member, and for forming the pivot for the latter; and a two-part pin extending through said loop, 55 and thereby having a hinge connection with said pivotal member, the points of said two-part pin being adapted to engage said keeper.

ALBERT JOHNSON.
